UNITED STATES PATENT OFFICE.

GUSTAV A. RAKOWSKY, OF DULUTH, MINNESOTA, ASSIGNOR TO AUTOMATIC UNLOADING CAR COMPANY, OF DULUTH, MINNESOTA, A CORPORATION OF MINNESOTA.

DUMP-CAR.

973,208.

Specification of Letters Patent. Patented Oct. 18, 1910.

Application filed July 19, 1909. Serial No. 508,493.

To all whom it may concern:

Be it known that I, GUSTAV A. RAKOWSKY, of Duluth, St. Louis county, Minnesota, have invented certain new and useful Improvements in Dump-Cars, of which the following is a specification.

My invention relates to that type of dump car, designed particularly for handling ore, receiving it at the mines and delivering it to the pockets at the dock.

The object of my invention is to simplify and improve the apparatus shown and described in Letters Patent of the United States, No. 899,682, issued to me September 29, 1908.

A further object is to provide a car, in which the load in the buckets will be transmitted directly to the body bolsters.

A further object is to provide a system of bracing in the car frame, which will resist lateral and longitudinal strain.

The invention consists generally in an improved car frame.

Further, the invention consists generally in improved means for locking the buckets in their horizontal position.

Further, the invention consists in improved means for tripping the locking means.

Further, the invention consists in means for bracing the side frames against inward pull and distortion.

Further, the invention consists in various constructions and combinations all as hereinafter described and particularly pointed out in the claims.

In the accompanying drawings, forming part of this specification, Figure 1 is a perspective view of a dumping car, embodying my invention, showing the buckets in their normal horizontal position, Fig. 2 is a similar view, illustrating the buckets in their dumping position, Fig. 3 is a detail view, partially in section, illustrating the means for locking the buckets in their horizontal position, and the mechanism for tripping the locking means, Fig. 4 is a similar view, showing the locking mechanism in its released or tripped position, Fig. 5 is a detail view of one of the locking latches.

In the drawing, 2 represents a car frame, having trucks 3. Upon each side of the car I provide lower side sills 4 composed preferably of channel bars, placed back to back

and riveted together. An arched truss frame, forming the upper side sills of the car is provided on each side, as indicated by the reference numeral 5, and also composed of channel bars placed back to back and riveted together. The upper portions 60 of each side sill 5 is substantially horizontal above the middle portion of the car and the ends of the side sills are turned downwardly at a suitable angle and secured to the car frame and the lower side sill, producing the 65 desired truss effect. Braces 6 of angle bars, having flanges placed back to back, are inserted between the horizontal portions of the upper side sills near the point where the angles are formed therein and their lower 70 ends are secured above the body bolster in position to transmit thereto the load carried by said upper sills. Gusset plates 6' are interposed between the channel bars, composing the sills 5 and the angle bars 6 and securely riveted thereto, thus forming a 75 rigid, substantial construction on each side of the car. Transverse web plates 7 are secured to the inclined portions of the sills 5 and extend across the car and have flanged 80 edges, which serve to stiffen the web. Cross tie lateral braces 8 and 8' connect the angles 6 and the web plates 7 respectively with the under frame of the car. An upright post 9 connects the web plate 7 and the body 85 bolster. Between these side frames, so formed, I arrange buckets 10 and 10^a and will refer to them and their connections by the same reference numerals with the addition of the exponent "a". These buckets 90 are composed of sheet metal, having trunnions 11 resting upon the side frames 5 directly above the braces 6 so that the load will be transmitted through the truss frame and braces to the bolster, and each bucket 95 is composed of sheet metal formed with the lines of its joints all running toward the dumping end of the bucket, the lower portion being constructed to drop down between the wheels, as will be set forth more in detail in my companion application herewith, filed July 19, 1909, Serial No. 508,494.

It will be understood that the car is provided with a bucket on each side of its transverse center, the buckets being similarly 105 mounted and each having a locking device and a fluid pressure controlled mechanism for operating the same.

The trunnions are so mounted on the buckets that they will be on the inner side of the vertical transverse plane of gravity, so that normally the buckets will swing to 5 their horizontal or closed position when empty.

For the purpose of locking the buckets in their closed position, I provide hangers 12 depending from the lower sills 4 and carrying pivoted latches 13 having weighted lower portions 14, which normally tend to swing the said latches outwardly to a releasing position. A vertically sliding bar 15 is provided on each side of the car having 15 lugs 16 thereon, which are adapted to drop down outside the free ends of the locking latches and hold them in their vertical or locking position. The bar 15 has a slot 17 therein for a guide pin 18 and when the bar 20 is raised a distance equal to the length of the slot 17, the lugs 16 will be raised out of the path of the locking latches to allow them to swing downward to a releasing position. Guides 19 are secured to the lower 25 side sills, between which the bars 15 are vertically slidable. The locking latches have seats 20 formed thereon near their pivots, and rails 21 are secured to the inner ends of the buckets and project outwardly therefrom on each side beyond the sills and are 30 adapted to enter the recesses 22 formed in the hanger 12 and engage the seats 20 and be held in said recesses by the locking latches until the bar 15 has been raised and 35 the latches released. The rails 21 have downwardly turned ends 23, which engage the hangers 12 and support the lower portions of the buckets, preventing them from sagging inwardly under the weight of the 40 load.

It is desirable to provide means for releasing the locking mechanism to allow the buckets to dump and then providing for the automatic dumping of the buckets themselves. I therefore, arrange a dog 24 in the lower side sills, in position to engage a lug 25 on the sliding bar 15. A rod 26 connects the dog 24 with an arm 27 on a shaft 28, which carries a lug 29. A link 30 is 45 adapted to receive said lug and is pivotally connected with a strap 31, which depends from a hollow piston 32, provided within a cylinder 33. A piston rod 34 is pivotally connected at 35 with the bottom of the 50 bucket and has a pin 36 at its other end that is slidable in a slot 37 provided in a bracket 38 on a piston head 39. A plate 40 is vertically slidable on pins 41 mounted on 55 said head against the tension of springs 42, which are coiled about said pins between 60 said plate and head. The pins 36 bear on the plate 40 and limit its upward movement. The cylinder below the piston head has an 65 intake pipe 43, connected through a suitable controlled valve, (not shown) with a

source of fluid pressure supply. When this pressure is admitted to the cylinder beneath the piston, the piston head will be pushed upward and during its initial movement, the piston 32 will slide in the upper head of 70 the cylinder, raise the strap 31, rock the shaft 28 and operate the dog 24 to lift the bar 15 and release the locking latches. All this will be accomplished without any movement whatever of the piston rod 34, the 75 lower end of which will slide in the slot 37 until the pin 36 has reached the limit of its movement, when further upward movement of the piston head will tilt the buckets to discharge their contents. With this apparatus, therefore, the initial movement of the piston head will trip the locking device to 80 release the buckets, while the subsequent movement of the piston head will tilt the buckets to discharge their load. The cylinders have outlets 44 at the top and air can be kept on the piston heads and the buckets held in a dumping position or a jarring movement imparted thereto by shutting off the fluid pressure to the cylinder and 85 then admitting it again, for the purpose of shaking the buckets and dislodging any material that may be adhering to the walls thereof. Generally however, as will appear in my companion application herewith, the 90 material in the buckets, owing to their shape and the direction of the lines of the bends or joints therein, will cause the material to flow easily and rapidly therefrom without further attention on the part of the operator. 95

I claim as my invention:—

1. The combination, with a car frame and body bolsters, of arched side sills provided on each side of the car and secured thereto 105 near the body bolsters, knee braces interposed between the upper horizontal portions of said truss sills and the car frame, and buckets provided between said sills and having trunnions journaled on said sills above and near said knee braces whereby the load 110 will be transmitted through said braces and sills to said bolsters.

2. The combination, with a car frame having lower side sills and body bolsters, of 115 upper side sills having downwardly turned ends secured to said lower sills, knee braces interposed between said lower sills and the upper horizontal portion of said upper sills, and said upper sills forming a truss frame, 120 gusset plates secured to the downwardly turned ends of said upper sills and to said knee braces, and buckets having trunnions journaled on said upper side sills between the downwardly turned ends thereof and 125 said braces, substantially as described and for the purpose specified.

3. The combination, with a car having lower side sills and body bolsters, of upper 130 side sills composed of channel bars placed

back to back and secured together and having downwardly turned ends secured to said lower sills and forming a truss effect, bracing means interposed between the horizontal 5 upper portion of said side sills and said lower sills; and buckets having trunnions journaled on said upper side sills near the downwardly turned ends thereof, whereby the load will be transmitted through said

10 truss frames to said bolsters.

4. The combination, with a car frame having lower side sills and a body bolster, of upper side sills composed of channel bars having downwardly turned ends secured to 15 said lower sills, said channel bars being placed back to back and secured thereto, knee braces composed of angle bars having their flanges secured together and interposed between the horizontal portion of said upper 20 side sills and said lower sills, gusset plates interposed between the bars comprising the downwardly turned ends of said upper side sills and between the flanges of said angle bars and secured to said channel bars, and 25 said angle bars, and buckets having trunnions journaled on said upper side sills above said downwardly turned ends and said braces, whereby the load on said trunnions will be transmitted to said body bolsters.

30 5. The combination, with a car frame, of upper side sills having downwardly turned ends secured to said frame, cross plates having their ends secured to the downwardly turned ends of said upper side sills and provided, 35 with flanged edges and extending transversely of the car, and buckets having trunnions journaled on said upper side sills above said transverse plates, substantially as described.

40 6. The combination, with a car frame having a body bolster and lower side sills, of upper side sills having downwardly turned ends secured to said lower sills and forming a truss frame, a web plate extending trans- 45 versely of the car and having its ends secured to the downwardly turned ends of said upper side sills, a post interposed between said web plate and said bolster, tie braces secured to said web plate and to said bolster, 50 and buckets arranged above said web plate and having trunnions journaled on the horizontal portion of said upper side sills.

7. The combination, with a car frame, of 55 tilting buckets journaled therein and arranged to tilt inwardly to discharge their load, a locking mechanism provided at the inner ends of said buckets near the bottoms thereof, fluid pressure controlled mechanism at the outer ends of said buckets and beneath the same for tripping said locking 60 means during the initial movement of said pressure controlled mechanism and tilting said buckets to discharge their contents during its subsequent movement, substantially as 65 described.

8. The combination, with a car, of tilting buckets mounted therein and arranged to swing inwardly to discharge their load, and locking mechanism provided at the abutting inner ends of said buckets and normally arranged to lock them in their horizontal position, a fluid pressure controlled mechanism comprising a piston and cylinder therefor located beneath said buckets, and means connecting said piston with a bucket, said piston being adapted during its initial movement, 70 to trip said locking mechanism and during its subsequent movement to tilt its bucket, substantially as described.

9. The combination, with a car, of buckets 75 mounted therein and adapted to tilt inwardly, hangers provided at the abutting inner ends of said buckets, locking latches carried by said hangers and provided with recesses having seats, bars secured to said buckets and having projecting ends adapted to enter the recesses in said latches and engage said seats, means for locking said latches in their raised position and temporarily preventing the disengagement of said 80 bars from said seats, and a fluid pressure controlled mechanism for releasing said latches to allow said buckets to tilt.

10. The combination, with a car, of buckets mounted thereon and arranged to tilt 85 inwardly to discharge their load, transverse bars secured to the inner ends of said buckets and projecting outwardly beyond the same and having downwardly turned ends, locking latches pivotally supported by said 90 car and having recessed seats therein to receive the projecting ends of said bars, the downwardly turned ends of said bars depending outside said latches and the seats thereon, means for locking said latches in 95 their raised position, and a fluid pressure controlled mechanism for releasing said latches to allow the tilting of said buckets.

11. The combination, with a car, of inwardly tilting buckets mounted therein, pivoted locking latches carried by said car, means mounted on said buckets and adapted to enter the recesses in said latches, a vertically sliding bar having lugs arranged to hold said latches in their raised position, a lever having means to engage said bars and lift same to release said latches, and mechanism within control of the operator for tilting said lever.

12. The combination, with a car, of buckets 110 pivoted thereon and adapted to tilt inwardly, a locking mechanism arranged to temporarily hold said buckets in their horizontal position, a cylinder, a piston therein having its stem connected with a bucket, 115 means operatively connecting said piston with said locking mechanism, and said piston being arranged to move a limited distance independently of its stem and actuate said locking mechanism to release said buck- 120 125 130

ets, the subsequent movement of said piston transmitting power through said stem to tilt the bucket.

13. The combination, with a car, of buckets mounted thereon and arranged to tilt inwardly, a locking mechanism provided at the abutting ends of said buckets and arranged to normally lock them in a horizontal position, a cylinder provided at each end of said car, a piston therefor, and means operatively connecting each piston with said locking mechanism, each piston having a stem connecting it with a bucket, and each piston having a limited movement with said connecting mechanism independent of its stem whereby said locking mechanism will be released during the initial movement of said piston and the bucket will be tilted during its subsequent movement, substantially as described.

14. The combination, with a car, of a bucket journaled therein, a locking mechanism arranged to lock said bucket in a horizontal position, a cylinder, a piston therefor operatively connected to said locking mechanism, said piston including a head and pins thereon, and a disk having holes to receive said pins, and springs interposed between said disk and said head, a slotted bracket secured to said head, a stem having a pin adapted to slide in said slot and bear on said disk, and said stem having a pivotal connection with said bucket, and said cylinder having a pipe through which fluid pressure is admitted below said piston, the initial movement of said piston head tripping said locking mechanism and its subsequent movement actuating said bucket through said stem.

15. The combination, with a car frame having lower side sills and body bolsters, of upper side sills having downwardly turned ends secured to said lower sills, knee braces interposed between said lower sills and said upper sills, gusset plates secured to said upper sills and to said knee braces, buckets having trunnions journaled on said upper side sills, substantially as described.

16. The combination, with a car, of inwardly tilting buckets mounted therein,

locking means provided at the inner ends of said buckets and adapted to lock them in their horizontal or closed position, fluid pressure cylinders having pistons arranged near the outer ends of said buckets, means operatively connecting said pistons with said locking mechanisms and with said buckets, said means operating successively to trip said locking means and tilt said buckets.

17. The combination, with a car, of buckets mounted thereon and arranged to tilt inwardly, transverse bars secured to the inner ends of said buckets and projecting outwardly beyond the same, locking latches having seats to receive the projecting ends of said bars, means for locking said latches in their raised position, and a fluid pressure controlled mechanism for releasing said latches to allow the tilting of said buckets.

18. The combination, with a car frame, of upper side sills having downwardly turned ends secured to said frame, cross plates having their ends secured to the downwardly turned ends of said upper side sills and extending across the car, and buckets having trunnions journaled on said upper side sills above said transverse plates.

19. The combination, with a car, of tilting buckets mounted therein and arranged to swing inwardly to discharge their load, a locking mechanism provided at the abutting inner ends of said buckets and normally arranged to lock them in their horizontal position, a fluid pressure controlled mechanism comprising a piston and cylinder therefor located near the opposite end of a bucket from said locking mechanism, and means connecting the piston of said cylinder with a bucket, said piston being adapted during its initial movement to trip said locking mechanism and during its subsequent movement to tilt its bucket.

In witness whereof, I have hereunto set my hand this 13th day of July 1909.

GUSTAV A. RAKOWSKY.
